UNITED STATES PATENT OFFICE.

ROBERT R. WEAVER, OF COLUMBUS, OHIO, ASSIGNOR TO THE RALSTON STEEL CAR COMPANY, OF COLUMBUS, OHIO.

CAR-UNDERFRAME.

1,247,913.

Specification of Letters Patent. Patented Nov. 27, 1917.

Application filed March 11, 1916. Serial No. 83,589.

To all whom it may concern:

Be it known that I, ROBERT R. WEAVER, a citizen of the United States, and a resident of Columbus, in the county of Franklin and 5 State of Ohio, have invented certain new and useful Improvements in Car-Underframes; and I do hereby declare the following to be a full, clear, and exact description of the invention, such as will enable others 10 skilled in the art to which it appertains to make and use the same.

This invention relates to improvements in underframes for cars and more particularly to the construction of the cross ties and the 15 connection of the same with the center girder and side sills,—the object of the invention being to so construct a cross tie of pressed channel steel and connect the same with the center girder and side sill in such manner 20 that a broad or extended connection of the cross tie with the center girder and side sill shall be afforded.

A further object is to so construct a cross tie for a car underframe that the same shall 25 have an integral part at one end projecting above the plane of the upper edge of the tie and so that it shall have an integral inwardly projecting part at its other end projecting below the lower edge of the tie, 30 whereby the connections of the tie with the center girder and side sill shall extend, respectively above and below the plane of the tie at respective ends thereof.

With these and other objects in view, the 35 invention consists in certain novel features of construction and combinations of parts as hereinafter set forth and pointed out in the claims.

In the accompanying drawings; Figure 1 40 is a transverse sectional view of a portion of a car underframe; Fig. 2 is a fragmentary view taken at right angles to Fig. 1, and Fig. 3 is a view illustrating a modification.

1 represents a center girder, and 2 a side 45 sill, the latter being shown as of channel construction.

A plurality of cross ties will be located between the center girder and the respective side sills intermediate of the bolsters, but as 50 such disposition of cross ties broadly, is well known in the art, it will suffice for the purposes of this case to illustrate a single cross tie and its connection with the center girder and one of the side sills.

55 The cross tie 3 comprises a steel beam

pressed up in channel form, having its web portion extended upwardly at the outer end as at 4 and having its web extended downwardly at its inner end as at 5. The upper flange 6 of the tie is omitted from a part of the upward web extension 4 and the lower flange 7 of the tie is omitted from a part of the downward web extension 5. At the outer end of the tie, its extended web is secured, throughout the vertical extension 60 thereof, to the web of the side sill 2, by means of an angle iron 8. At its inner end, the cross tie may be made with an integral vertical flange 9 throughout the full extended end portion of the tie, and securely riveted 65 to the center girder.

Instead of providing the inner end of the tie with an integral vertical flange, said flange may be omitted and the tie secured to the center girder by means of an angle iron 70 75 10, as shown in Fig. 3.

It will be observed that the upper flanged edge of the side sill is approximately in horizontal alinement with the top of the center girder, being but slightly above the same 80 so as to be on the floor line, and Z-beams may be mounted on the cross ties to support intermediate portions of the flooring.

It will also be observed that the outer extended end of the cross tie is disposed wholly 85 below the upper edge of the side sill and its sole function is to provide for an extended connection of the tie with the side sill.

Having fully described my invention what I claim as new and desire to secure by Letters-Patent, is:

1. The combination with a center girder and a side sill, of a channel beam constituting a cross tie extending from the center girder to the side sill, said beam having its 95 web portion extended vertically in opposite directions at respective ends, one of said vertically extended webs being confined between the edges of the side sill and of less height than the depth of said side sill and secured to the latter, and the vertically extended web portion at the other end of the tie secured to the center girder and having a height less than the depth of the latter and confined between the upper and lower edges thereof. 100

2. The combination with a center girder, and a channel side sill having its flanges projecting inwardly, of a channel beam constituting a cross tie confined below the upper edges and above the lower edges of the cen- 110

ter girder and side sill, the web of said channel beam being extended upwardly at the outer end of said beam, and confined between the flanges of the side sill, means securing said extended web to the side sill between the flanges thereof, the web of said beam being extended downwardly at the inner end thereof and having a height less than the depth of the center girder, and means securing said last-mentioned extended web to the center girder.

3. The combination with a center girder and a side sill, of a cross tie between the center girder and side sill, said cross tie comprising a beam having flanges at its upper and lower edges, the upper flange being omitted at the outer end of the tie and

the lower flange being omitted at the inner end of the tie, the web of the tie being extended vertically in opposite directions at the respective ends of the tie where portions of the flanges of the tie are omitted, means securing the extended web at the outer end of the tie to the side sill, and means securing the extended web at the inner end of the tie to the center girder.

In testimony whereof, I have signed this specification in the presence of two subscribing witnesses.

ROBERT R. WEAVER.
